SPOON

Michael C. Fina, Forest Hills, N. Y.

Application August 28, 1953, Serial No. 26,620

Term of patent 14 years

(Cl. D54—12)

To all whom it may concern:

Be it known that I, Michael C. Fina, a citizen of the United States residing in Forest Hills, county of Queens, in State of New York, have invented a new, original, and ornamental Design for a Spoon, of which the following is a specification, reference being had to the accompanying drawing, forming a part hereof.

In the drawing:

I claim:

The ornamental design for a spoon, as shown.
